UNITED STATES PATENT OFFICE.

WILLIAM L. BRYANT AND ERNEST C. LUNING, OF TRINIDAD, COLORADO.

SHAVING-BRUSH.

1,259,207.

Specification of Letters Patent. Patented Mar. 12, 1918.

Application filed March 1, 1917. Serial No. 151,704.

To all whom it may concern:

Be it known that we, WILLIAM L. BRYANT and ERNEST C. LUNING, citizens of the United States, and residents of Trinidad, in the county of Las Animas and State of Colorado, have invented a certain new and useful Improvement in Shaving-Brushes, of which the following is a specification.

Our present invention relates generally to 10 shaving brushes, and more particularly to reservoir brushes of this nature, having means to retain a quantity or supply of shaving soap in plastic form, together with adjustable means for feeding the same to 15 the brush, including means whereby to effectively cut off the feed when the brush is in use.

A further object of our invention is to provide a shaving brush in which the brush 20 head is separable from the handle portion or reservoir, and the latter is, therefore, capable of separate sale with a removable closure, removal of which enables the user to apply his brush head to the same, the reservoir 25 being of course renewable in this way at a cost comparatively small in respect to the cost of the entire shaving brush.

Further objects and the attendant advantages of our improved shaving brush will 30 be better understood from the following description thereof, reference being had to the accompanying drawing forming a part of this specification, and in which—

Figure 1 is a side elevation of our improved 35 shaving brush, showing the brush protecting tube in place and partly broken away and in section;

Fig. 2 is a longitudinal section through our improved shaving brush as in use;

Figure 3 is an enlarged section of a portion thereof;

Figure 4 is a cross section taken substantially on line 4—4 of Fig. 2;

Fig. 5 is a detail cross section through the 45 nozzle taken substantially on line 5—5 of Fig. 3, and

Fig. 6 is a side view of a portion of the reservoir with its closing cap in place, previous to the application of the brush head.

50 Referring now to these figures, our invention contemplates the provision of a cylindrical handle portion 10, which forms a reservoir, its outer closed end 11 being provided with an axially disposed bearing

55 12 for the rear end of a threaded shaft 13, the latter extending forwardly through the

cylinder 10, with a collar 14 secured thereon at the inner side of the bearing 12, and a knurled head 15 secured thereto in the rear of the bearing 12, thus permitting the shaft 60 13 to be rotated by rotating the head 15 and at the same time preventing its longitudinal movement.

Within the cylinder 10 is a follower 16 having an axial threaded opening to receive 65 the shaft 13, and having a peripheral recess engageable with an inner longitudinal rib 17 of the cylinder 10, which prevents rotation of the follower and thus forces the same to move longitudinally of the cylinder when 70 the screw shaft 13 is rotated.

At its opposite end the handle portion or reservoir 10, which is preferably formed from sheet metal, is provided with embossed threads 18, the brush head 19 having its 75 outer surface formed for engagement within the threads 18, and a cap 20 having boss threads for engagement around the threads 18, so that with the brush head removed, the reservoir or handle 10 may be closed by the 80 cap 20 for a purpose to be presently described.

The brush head 19 formed of any suitable material, has the usual forwardly extending bristles 21, and is provided with a 85 central recess 22 in its inner face, and an axial opening 23 leading from the recess 22, and communicating at its outer end with a cavity in the outer face of the brush head adjacent the inner ends of the bristles and provided with undercut walls to receive the inner flared ends 24 of a nozzle 25, the latter having a longitudinal feed slot 26, and projecting within and lengthwise of the bristles 21. 95

In use the plastic soap is placed within the handle portion or reservoir 10, forwardly of the follower 16, as indicated at 27 in Fig. 2, so that upon rotation of the shaft 13 and corresponding advance of the follower 16, the plastic soap is forced through the channel 23 of the brush head 19 and the feed opening 26 of the nozzle 25. Immediately, however, upon the application of the shaving brush in use, the movement 105 tends to close the feed opening 26 of the nozzle 25, so as to shut off any further feed and thus obviate an over supply of the material 27, the nozzle being flexible and its slot 26 normally closed. 110

It is obvious from this that the nozzle 25 as well as the brush head 19 and the handle

portion or reservoir 10 may be formed of any suitable material and in various sizes to suit the needs and desires in use, and it is further obvious that, by virtue of the detachment of the head 19, the reservoir 10, closed by the cap 20, may be sold separate from the brush head 19, thus permitting the user to purchase a fresh supply of shaving material within a reservoir from time to time, in connection with which the brush head is capable of ready connection when the closing cap 20 has been removed.

A brush protecting cylinder 28 may also be supplied, having the general form of a cylinder similar to the form of the reservoir or handle portion 10, provided at one end with threads 29, as seen in Fig. 1, for connection with the threads 18 of the reservoir or handle portion 10, and closed at its outer end except for a small ventilating aperture

30, the use of the cylinder 28 protecting the bristles 21.

We claim:

A shaving brush including a brush head having bristles projecting therefrom, and 25 provided with an axial feed channel, said brush head being otherwise of solid construction and having a cavity in its outer face adjacent the inner ends of the bristles and around the outer end of the said channel, said cavity having undercut walls, and a nozzle extending into the bristles and provided with a flared inner end detachably seated in the cavity of the head, said nozzle having a longitudinal feed opening communicating with the feed channel of the head. 30 35
